WITNESS:

J. B. Brady

INVENTOR.

Carl C. Hanson

UNITED STATES PATENT OFFICE.

EARL C. HANSON, OF WASHINGTON, DISTRICT OF COLUMBIA.

UNDERGROUND AND SUBMARINE ANTENNA.

1,388,336.

Specification of Letters Patent.

Patented Aug. 23, 1921.

Application filed February 25, 1919. Serial No. 279,078.

To all whom it may concern:

Be it known that I, EARL C. HANSON, a citizen of the United States, residing at Washington, in the District of Columbia, have invented certain new and useful Improvements in Underground and Submarine Antennæ, of which the following is a specification, reference being had therein to the accompanying drawing.

10 My invention relates to radio communication and more specifically to an underground and submarine antenna for use in the reception of radio signals.

15 The object of this invention is to provide an underground and submarine antenna which is not responsive to strays.

20 A further object of this invention is to establish an underground and submarine antenna of greater efficiency than heretofore obtainable in such underground systems.

Other and further objects will become apparent as the specification progresses.

25 Referring to the accompanying drawings, in which like reference characters have been used to designate like parts throughout the several views:

30 Figure 1 is a view in section showing one arrangement of an underground and submarine antenna within a conduit in which the antennæ are formed in spirals;

35 Fig. 2 shows a modified arrangement of the antennæ within the conduit in which a series of lumped inductances, shunted by condensers, are inserted at intervals throughout the length of the conductors;

40 Fig. 3 shows the conduit inclosing an antenna having only lumped inductances inserted at intervals throughout its length.

45 Referring now particularly to Fig. 1 I have shown conduit 2 buried in the earth 1, and extending in opposite directions. The antennæ are shown at 5 and 6, positioned within the oppositely extended conduit and connected to radio receiving apparatus by means of leads 3 and 4, respectively.

50 The antennæ are formed of spiral inductances extending throughout the length of the conduit.

55 In Fig. 2 the antennæ are shown made up of a series of inductance coils 5 and 6, spaced at intervals in the length of conduit. These inductances are concentrated at intervals in the antennæ and each shunted by a suitable capacity 7 and 8, respectively.

Fig. 3 shows an underground or subma-

rine antenna made up of a series of concentrated inductances 5, spaced at intervals throughout the length of the antenna conductor. In this case the antenna is shown in conjunction with an earth plate 6, connected with radio receiving apparatus by means of lead 4, in lieu of the opposite antenna conductor shown in Figs. 1 and 2.

The underground or submarine antennæ are constructed in the form of spirals to eliminate the response of such an antenna system to strays, as encountered in radio telegraph and telephony. The antenna shown in Fig. 1 will respond favorably to sustained wave transmitting systems. This antenna when once set in oscillation will continue to oscillate in its own periodicity. Any extraneous strays impinging on the antennæ will not actuate the radio receiving apparatus because of the electrical inertia characteristic of the antennæ. The highly damped oscillations produced by strays will be prevented from reaching the receiving apparatus due to the retarding effect of the high inductance of the antennæ. In Figs. 2 and 3 the same principle exists. The rapidly damped oscillations due to strays are retarded, while persistent oscillations of continuous waves are unobstructed.

85 In Fig. 2 the inductances are lumped instead of being distributed in the antennæ, and each inductance shunted by a condenser. The condensers are adjusted to such capacity in conjunction with predetermined inductances that individual tuned oscillatory circuits are formed throughout the length of the antennæ which make it possible for sustained oscillations to pass, but which act as retarding means to strays.

90 Fig. 3 shows a series of lumped inductances in one underground or submarine antenna which can be used with a similar underground system or an earth connection, as shown at 6.

100 Having thus described my invention, what I claim is:

1. A wireless system for signaling by electro-magnetic waves comprising antennæ formed of free ended spirals extending in opposite directions substantially parallel to and buried under the surface of the earth.

105 2. A wireless system for signaling by electro-magnetic waves comprising antennæ formed of series of inductances electrically free at their outer extremities disposed in conduit, said inductances being spaced

apart throughout the length of the antennæ and extending in opposite directions substantially parallel to and buried under the surface of the earth.

5. 3. A wireless system for signaling by electro-magnetic waves comprising antennæ disposed in conduit and including a series of lumped inductances with shunted capacities electrically free at their outer extremities extending in opposite directions substan-

tially parallel to and buried under the surface of the earth.

4. An underground antenna for radio signaling comprising a pair of extended inductances connected to radio signaling apparatus and buried horizontally in the earth, said inductances having their axes alined in opposite directions and their ends electrically free. 15

EARL C. HANSON.
